(57) **CLAIM**

The ornamental design for a clinical analyzer, as shown and described.

DESCRIPTION

FIG. 1 is a front, top and right side perspective view of a clinical analyzer with its environment showing our new design;

FIG. 2 is a front elevational view thereof with its environment;

FIG. 3 is a rear elevational view thereof with its environment;

FIG. 4 is a left side elevational view thereof with its environment;

FIG. 5 is a right side elevational view thereof with its environment;

FIG. 6 is a top plan view thereof with its environment;

FIG. 7 is a bottom plan view thereof with its environment;

FIG. 8 is a reference front, top and right side perspective view thereof shown in an opened position with its environment;

FIG. 9 is an enlarged front, top and right side perspective view thereof without environmental matter;

FIG. 10 is an enlarged front elevational view thereof without environmental matter;

FIG. 11 is an enlarged rear elevational view thereof without environmental matter;

FIG. 12 is an enlarged left side elevational view thereof without environmental matter;

FIG. 13 is an enlarged right side elevational view thereof without environmental matter;

FIG. 14 is an enlarged top plan view thereof without environmental matter; and,

FIG. 15 is an enlarged bottom plan view thereof without environmental matter.

The broken lines in FIG. 1-8 views are included for the purpose of illustrating environmental subject matters, and the broken lines in FIG. 15 views are included for the purpose of illustrating portions of the clinical analyzer that form no part of the claimed design. None of the broken lines form a part of the claimed design.

1 Claim, 14 Drawing Sheets
